[57] **CLAIM**

The ornamental design for a compressor shroud, as shown and described.

DESCRIPTION

FIG. 1 is a top plan view of a compressor shroud showing the new design;

FIG. 2 is a front plan view thereof;

FIG. 3 is a back plan view thereof;

FIG. 4 is a bottom view thereof; and,

FIG. 5 is a right side plan view thereof, the left side being a mirror image thereof.

The broken line showing of attachment tabs in FIGS. 2, 3 and 5 are for illustrative purposes only and forms no part of the claimed design.
